STRUCTURAL INSERT

Herman E. Eichner, Palmyra, N. J.

Application January 23, 1932, Serial No. 588,408

4 Claims. (Cl. 72—105)

The present invention relates to building structure that includes a masonry wall, floors etc. of precast or premolded building blocks and adjacent structure of wood or the like fastened to the mason work, the building blocks usually comprising commercial units of concrete, gypsum or other composition, and the present invention may be considered to some extent a continuation of the subject matter of the applicant's 10 U. S. Patent No. 1,798,197, entitled "Structural member".

A purpose of the invention is to provide commercial masonry units of the character indicated with an adaptation to receive and strongly hold 15 nails, screws or the like from adjacent structure.

A further purpose is to cast a preferably fire-proof and preferably all-metal nail-holding unit in a commercial block of the character indicated.

A further purpose is to provide precast commercial blocks of the character indicated with one or more nail-holding inserts from one or more 20 of the side surfaces thereof and located for best registry with the different usual structural members that are normally to be fastened to a masonry wall adapted to be formed of the blocks.

A further purpose is to cast nail-holding inserts in blocks of the character indicated, locating the 25 inserts to permit an easy nailing of furring strips, corner beading, nailing blocks and the like to walls built of the blocks as well as an easy anchoring of veneer brickwork or the like to the wall.

A further purpose is to provide a block of the character indicated with a nail-holding insert 30 adjacent one or more of the corners or/and at an intermediate portion of one or more of the side surfaces of the block.

A further purpose is to provide one or more of the side surfaces of a block of the character indicated with a diagonal strip portion along which it is adapted to receive and hold nails or the like.

Further purposes will appear in the specification and in the claims.

45 Figures 1 and 2 are fragmentary perspective views of different partially constructed walls that include block units made in accord with my invention, the views illustrating some of the many ways of applying the invention.

50 Figure 3 is an enlarged scale perspective view of a precast building block or unit embodying optionally variant detail features of the invention.

Figure 4 is a vertical section to enlarged scale 55 taken upon the line 4—4 of Figure 1.

Figure 5 is a horizontal section taken upon the line 5—5 of Figure 4.

Figures 6 and 7 are enlarged scale perspective views generally similar to Figure 3 but illustrating somewhat different placements of my nail-holding inserts.

Figure 8 is a perspective view showing one form of the all-metal nail-holding inserts that are intended to be shown conventionally in the blocks of Figures 3, 6 and 7 as any inserts adapted to embody the invention.

Figure 9 is a perspective view showing a different and very excellent form of all-metal nail-holding insert,—or nailing pad, the structure being optionally in section like that of a structural member, disclosed and claimed in the applicant's patent above referred to.

Figure 10 is a fragmentary side view of a nailing pad of the form of Figure 9, with the outer plate removed to show one of the inner and deformed sheets.

Figure 11 is a section taken upon the line 11—11 of Figure 10.

Figure 12 is a perspective view of another form of insert, that advantageously differs from that of Figure 9 in omitting portions highly desirable in the structural member of the patent but not needed in an insert for a building block.

Figures 13 and 14 are elevations of illustrative insert blocks which may be used.

Figure 15 is a transverse section of another form of insert.

Like numerals refer to like parts in all figures.

Describing in illustration and not in limitation and referring to the drawings:—

In the past, structural members of wood or the like, adjacent masonry walls of precast or molded building blocks have been nailed to the masonry wall by means of blocks or expansion bolts inserted at intermediate blocks of the wall or have been nailed directly to the blocks or even to mortar or cement intermediate the blocks.

The insertion of inserts intermediate the blocks, and the nailing to mortar or cement intermediate the blocks have both proven unsatisfactory and as a result, the blocks have been made of material selected for an adaptation to take and hold nails, rather than for strength. This has to a considerable extent limited the use of precast blocks to outlying districts in that the requirement that the blocks shall be adapted to take and hold nails has resulted in blocks of insufficient strength for use in city buildings.

The molded blocks of a wall made in accord with my invention need not all include the

nailing inserts, the inserts being most desirably located merely wherever it may be desirable to nail to the wall, so that whether or not any individual block should include one or more nail-
5 ing inserts will usually depend upon the location of the block in the masonry wall with respect to adjacent structure to be nailed to the wall, and will also depend upon the character of the adjacent structure to be nailed to the masonry structure and also upon the dimensions of the blocks.
10

It will be understood that the precast blocks may vary widely with respect to dimensions, hollow spaces and molding material and the illus-
15 trated blocks are intended for a conventional showing of any blocks suited to the invention.

In Figure 1 the walls 16 and 16' may be considered as respectively an outside and an inside wall. Usually an outside wall will receive furring strips 17 upon the inside so that a plaster portion 18 of
20 the wall may be spaced inwardly from the mason block structure in order to provide an air space to prevent inward travel of dampness through the wall.

The wall includes in Figure 1 a masonry portion made up of precast blocks 19. In registry with the location of the furring strips 17 I provide blocks that present outwardly directed nail-
25 ing pads 20 well adapted to receive the nails from the furring strips. Adjacent the door structure at 21 I show blocks carrying inserts generically indicated at 20 to receive nails from the framework of the door. Likewise at the window 22 the blocks 19 carry corner inserts 20 to receive the
30 nails from the frame of the window.

Where the spacing yielded by the furring strips is not desirable because there is no need of protection against moisture the plaster is applied directly to the building blocks but some means of attachment is still needed where a base-board for example, is to be applied. For this purpose short nailing blocks such as are shown at 23 in
40 Figure 4 may be used comparable in thickness with the thickness of the plaster and fastened to the inserts 20 as by nails 24.

The base-board is then fastened to these nailing blocks in any suitable manner as by nails 25.

In Figure 2 the view of the wall toward the observer is an outside wall as distinguished from an inside wall in Figure 1. The outside wall is shown as faced with brick and the brick wall may be anchored by any suitable fastening which engage in the nailable inserts 20 within the blocks.

The brick wall is constructed to a point where one of the faces or ends of the brick crosses the insert and the anchor is then put in after which the laying of the brick is continued to encase the anchor within the wall.

In theory the insert may be located anywhere within the block so that its face is available from the outside face of the block. The location of the insert should correspond with the convenience of the operator in placing the adjoining structure.

For some purposes it will obviously be more convenient to have the inserts in or near the middle of the face whereas in other locations it should be located partly in one face of the block and partly in another, as for example partly in what is intended to be the outside wall face and partly in an end, top or bottom wall face adjoining.

Where the inserts have greater length than width of exposure—as is of course ordinarily most desirable—the longer dimension may extend in

any direction as compared to the face of the block. In Figure 2 part of these inserts are shown at 20' as diagonally extended and located in the middle of the block and part of them are shown as at 20² as lying partly in the end of the block and partly in the face of the block to which the door or window structure is attached. It will be noticed that the corner inserts are horizontal and not diagonal and of course the inserts at the middle of the block could be horizontal also.
80
85

There is an advantage in putting an insert in diagonally in that it stretches over a greater extent vertically and also a greater extent horizontally than would be true of a straight insert as distinguished from a diagonal insert, making it suitable attachment throughout a wider range of distance both with horizontally arranged and with vertically arranged attached structure.
90

This is well illustrated in Figure 2 where the diagonal inserts have a longer vertical range of attachment than the thickness of the brick, insuring opportunity for location of an anchor at each insert.
95

It is of course convenient to space the inserts in agreement with the spacing of the attachments which are to be held by them. This may be done automatically by the separation of the inserts to distances corresponding with the lengths, widths and thicknesses of the blocks but
100 may be specially designed and secured by predetermined spacing of inserts within the blocks themselves to correspond with lengths of brick or strong line separation, etc.

At the outer corner 26, Figure 2 and in other like locations it is common to apply a metal corner bead which must be attached to the adjoining wall.
110

The location of the inserts 20² at the corners of the blocks makes it possible for this pad to
115 be nailed to both faces of the block at the corner.

In Figures 3, 6 and 7 blocks are shown which are intended to be of standard type and are herein treated as conventional blocks inasmuch as my invention can be applied to any form of
120 block, whatever the shape or type of material of which the block is made.

The insert provides a decidedly better nailing surface even for a block which already is capable of receiving a nail—though poorly—such as
125 a cinder block, though it finds greater utility in making a block of hard material incapable of receiving a nail otherwise available for nailing purposes. It is intended to apply to all kinds of molded blocks regardless of their material and
130 regardless of their type, as examples only of different materials from which the block may be made, and all of them incapable of receiving nails otherwise. I have illustrated a concrete
135 block in Figure 3, a plaster block in Figure 6 and a terra cotta or hollow tile block in Figure 7.

The showing of all of these blocks as hollow does not however mean that this has any part
140 specially in my invention as my inserts will serve as well in a completely solid block or tile as in a hollow block or tile. Nor does the purpose for which the block or tile is used affect the value of the invention where outside structure
145 is to be nailed or anchored to it. The character of use is widely divergent as my invention is applicable not only to what are known as building blocks but to such molded shapes for example as are used for chimney construction, in
150

vertical placement and for conduit use in horizontal placement.

The location of the insert within the individual block will depend upon the dimensions and the intended use of the block and the character of insert will be suited, of course, not only to the range of nail surface desired but to the strength of nail retention and the sizes of nails intended to be used. For light work the wooden blocks of Figure 13 may be quite acceptable whereas for more difficult retention the fiber form of Figure 14 or one of the metal forms might be necessary, or at least much desirable. All of the metal forms have the advantage of resistance against fire injury to a much greater extent than the forms of Figures 13 and 14.

One form of insert is shown in Figure 8 in which corrugated walls 27 are reversely bent at 28 to form a casing having corrugations extending in one direction and similarly corrugated walls 29 are placed between the casing walls and with the corrugations extending in opposite directions. The flanges 30 limit movement of the insert within the block as the insert is being placed.

One objection to the form of Figure 8 lies in the fact that the material of the block is free to enter the spaces 31 of the outer wall corrugations, preventing use of these spaces for nail reception and reducing the resilience of the rest of the corrugated structure. This is corrected in the insert of Figure 7 in which outer plane plates 32 cover the corrugations of the sheet material 27 protecting against engagement of the material of the block with the corrugated surfaces.

In Figure 9 an insert is shown having flanges 30 and 30' and plates at opposite ends suited to extend through a thin block and receive nails from either surface 33 or surface 34. Its filling material may be of any suitable form like those illustrated or different from them. The different inserts shown are not intended to form a complete disclosure of the different types which can be used, but are intended as illustrative only to show that a wide variety can be used acceptably, depending upon the conditions met and the preference of the designer.

In Figures 10 and 11 one outer wall 35 only is shown and a single flange 30 permitting the depression of the insert within the block before it is solidified and limiting the distance of introduction of the insert by the flange. The filling material here comprised deformed plates 36 having oppositely projecting prongs 37 and spaced plate from plate by sheets 38 to prevent the deformed plates from being compressed too solidly together to give the needed resilience. Any number of these deformed plates can be used before the next outside wall 35 is placed.

As will be seen the forms of Figures 8, 9 and 11 are suitable for use with nail insertion from either of two directions within parallel planes, as illustrated by the nail insertions at 39 and 40 in Figure 9.

The form of Figure 12 corresponds with what is shown of the filling in Figure 11, i. e. using two deformed sheets or plates, but uses a different outer casing at 41 similar to that of Figure 9 except that as in the corrugated outer casing

of Figure 8 it is reversely bent at 42. This form also is slightly flanged at 43 and 44 and is desirably made of spring metal so that its spring may be effective additionally to the spring of the deformation of the plates 36 to hold the content within the outer casing and so far as there may be outward movement permitted by the material of the block to provide additional resilience through movement against the spring and in an outward direction with respect to the plates.

In Figure 15 a form is shown corresponding generally with that of Figure 12 but with a single deformed sheet 36 only and without any spacing sheet. In it the outer casing 41 is punched at 45 to assist in holding the deformed plate in position and this can, of course, be done also in Figure 12.

In Figures 13 and 14 non-metallic forms are shown, a wood insert appearing in Figure 13 at 46 and a fiber insert 47 shown in Figure 14. An anchor is shown at 48.

It will be evident that the invention may be marketed in the form of blocks containing the resilient inserts or the resilient inserts may be supplied to licensed manufacturers of blocks for insertion by them.

By reference to "nailing" it is, of course, intended to include any form of fastening by projections fitting into the insertions and retained by engagement with the material of the insertions whether this is effected by nails or otherwise.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. A resilient metal insert comprising a plurality of parallel resilient plates alternately in right angle relation to each other adapted to receive nails in directions at right angles to each other held at the edge of a block so as to present nailing surfaces in adjoining block surfaces at right angles to each other.

2. A nailing insert for a block comprising deformed metal plates held parallel to each other in the block and providing a plurality of laterally spaced nail-receiving openings, the projections of the deformation providing resilience in the insert and gripping the nail in position.

3. A resilient insert for a molded block comprising outer insert casing walls and a resilient metal filler within the casing walls, the filler comprising a single deformed sheet having oppositely extending resilient projections on the faces of the sheet.

4. A resilient insert for a molded block comprising outer insert casing walls and a resilient filler within the casing walls, the filler comprising a plurality of spaced deformed metal sheets having the deformations extending in opposite directions on the faces of each sheet.

HERMAN E. EICHNER.
